HAND PAINTED RIBBON TIE OR THE LIKE

Jean Faber, Flushing, N. Y.

Application December 13, 1950, Serial No. 13,419

Term of patent 7 years

(Cl. D3—16)

To all whom it may concern:

Be it known that I, Jean Faber, a citizen of the United States, residing at Flushing, New York, in the county of Queens, and State of New York, have invented a new, original, and ornamental Design for a Hand Painted Ribbon Tie or the like, of which the following is a specification, reference being had to the accompanying drawing, forming part thereof.

In the drawing the figure is a face view of a hand painted ribbon tie or the like, showing my new design.

The essential features of my design reside in the portion shown in full lines.

I claim:

The ornamental design for a hand painted ribbon tie or the like, as shown and described.

JEAN FABER.
